US0D1070486S

(12) **United States Design Patent** (10) **Patent No.:** **US D1,070,486 S**
(45) **Date of Patent:** **** Apr. 15, 2025**

(54) **LID**

(71) Applicant: **Ze Fang**, Anhui (CN)

(72) Inventor: **Ze Fang**, Anhui (CN)

(**) Term: **15 Years**

(21) Appl. No.: **29/973,129**

(22) Filed: **Nov. 14, 2024**

(51) **LOC (15) Cl.** **07-02**

(52) **U.S. Cl.**

USPC **D7/392.1**

(58) **Field of Classification Search**

USPC D7/392.1, 392, 387, 391, 396.1, 396.2,

(57) **CLAIM**

The ornamental design for a lid, as shown and described.

DESCRIPTION

FIG. 1 is a front, right, and top perspective view of a lid, showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the lid that form no part of the claimed design.

1 Claim, 8 Drawing Sheets
